UNITED STATES PATENT OFFICE.

WILLIAM H. OSMER AND ROBERT M. GRIER, OF BONFILS STATION, MO.

HORSE-COLLAR PAD.

SPECIFICATION forming part of Letters Patent No. 284,658, dated September 11, 1883.

Application filed June 25, 1883. (No model.)

To all whom it may concern:

Be it known that we, WILLIAM H. OSMER and R. MONROE GRIER, citizens of the United States, residing at Bonfils Station, in the county of St. Louis and State of Missouri, have invented a new and useful Horse-Collar Pad, of which the following is a specification.

The nature of our invention consists in the construction and arrangement of a sectional sweat-pad for horse-collars, with means for attaching it to the horse-collar, as will be hereinafter more fully set forth.

In order to enable others skilled in the art to which our invention appertains to make and use the same, we will now proceed to describe its construction and operation, referring to the annexed drawings, which form a part of this specification, and in which—

Figure 1 represents a front elevation of our improved collar-pad. Fig. 2 is a rear elevation; Fig. 3, a detail perspective of pad with sections removed. Fig. 4 is a detail perspective of strip, and clasp. Fig. 5 is a detail elevation of strip, showing loops for holding the pads and hooks or eyelets and laces forming said loops.

Similar letters refer to similar parts throughout the several views.

A represents a horse-collar with our improved pad attached.

B represents the pad, formed by placing a series of detachable sections upon the strip F, which may be of fabric, leather, paper, rubber, or metal, or a combination of the same.

To the strip F are secured the sections C in loop D, formed by drawing laces through hooks or eyelets E. Sections C are held firmly upon strip F by drawing the laces tight; or the sections C may be buttoned, hooked, or otherwise secured to the strip F in a manner to be easily detached, which is the object designed. The detachable sections C may be placed upon either side of strip F—that is, sections C may be applied as shown in the drawings, or upon the opposite side of strip F. The plan shown and described is deemed preferable, from the fact that by the removal of the sections c, which will be to relieve the pressure upon an abrasion or wound upon the

shoulder of the animal, the remaining sections 50 c will hold strip F and the horse-collar apart from and clear of the wound, which allows a free and constant passage of air over the wound, with a tendency to sooth and rapidly heal the same—a result which cannot be accomplished by the use of ordinary sweat-pads, or those having sections inclosed. The complete device is then attached to and rigidly held in place upon the horse-collar by the metal clasps H, which may be riveted or 55 otherwise fastened to strip F separately, or in connection with the stiffening-strip, as shown in Fig. 4. These stiffening-strips are applied to strip F to hold the same stiff and in place when a section is withdrawn, as shown in Fig. 65 3; and may be of metal, wood, whalebone, or other suitable material. Clasps H are bent in circular form to grasp the front roll of the horse-collar and hold the pad in place, as shown in Fig. 1.

I represents a separate section of our improved collar-pad, composed of detachable sections J, adapted and applied as in the case of collar-pad B, hereinbefore specified.

Instead of strip F, with pieces of metal to 75 stiffen the same, we may use a wire skeleton frame or wire-cloth without departing from the spirit of our invention.

We are aware that the application to horse-collars of detachable sectional pads is not new, 80 as formerly a series of detachable sectional pads have been tied upon the horse-collar. Bandages have also been placed thereon, and holes have been cut in the horse-collar, leaving an open space for the protection of sores 85 and abrasions, while more recently a device inclosing a series of detachable sectional pads in a case or envelope has been patented; hence we do not claim, broadly, a series of detachable sections for horse-collar pads; but 90

What we do claim, and desire to secure by Letters Patent, is—

1. In a sweat-pad for horse-collars, the combination, with the strip F, of fabric or other suitable material, provided with the detachable sections C, of the metal clasps H, adjusted to secure the pad to the collar, all substantially as shown and described.

2. The combination, with a horse-collar, of the pad having removable sections, and the attaching metal clasps adapted to grasp the small roll of the collar and hold the pad in 5 place, all substantially as set forth.

3. A sweat-pad for horse-collars, consisting of a foundation strip of fabric or other suitable material, and a series of detachable sectional pads, provided with metallic clasps suitably secured to the strip and adapted to grasp the roll of a collar, all substantially as set forth.

In testimony that we claim the foregoing we have hereunto set our hands this 20th day of June, 1883.

WILLIAM H. OSMER.
R. MONROE GRIER.

In presence of—

JENNE N. GRIER,
CARRIE L. GRIER:
